UNITED STATES PATENT OFFICE

167,962

DINNER PLATE OR SIMILAR ARTICLE

Peggy S. Vreeland, Westfield, N. J., assignor to Onondaga Pottery Company, Syracuse, N. Y., a corporation of New York

Application November 3, 1951, Serial No. 17,249

Term of patent 14 years

(Cl. D44—15)

To all whom it may concern:

Be it known that I, Peggy S. Vreeland, a citizen of the United States, residing at Westfield, State of New Jersey, have invented a new, original, and ornamental Design for a Dinner Plate or Similar Article, of which the following is a specification, reference being had to the accompanying drawing, forming part hereof.

The drawing is a plan view of a plate of conventional configuration showing my new design. The dominant feature of my design resides in the ornamentation in the center of the plate depicting the cavorting lamb, as shown.

I claim:

The ornamental design for a dinner plate or similar article, as shown and described.

PEGGY S. VREELAND.
